UNITED STATES PATENT OFFICE.

CARL B. ERICKSON AND CARL J. WITT, OF CHICAGO, ILLINOIS.

LOCKING DEVICE FOR POCKETS.

Application filed July 3, 1922. Serial No. 572,413.

To all whom it may concern:

Be it known that we, CARL B. ERICKSON and CARL J. WITT, citizens of the United States, and residents of the city of Chicago, in the county of Cook and State of Illinois, have invented certain new and useful Improvements in a Locking Device for Pockets; and we do hereby declare that the following is a full, clear, and exact description of the same, reference being had to the accompanying drawings, and to the numerals of reference marked thereon, which form a part of this specification.

This invention relates to a locking device for pockets.

It is an object of this invention to provide a pair of mutually co-operative members adapted for attachment to opposite inner sides of a pocket or the like for locking the pocket against the removal of articles therefrom, especially by theft, with means extending around on the inner side of a garment for unlocking said members for disengagement.

It is a further important object of this invention to provide means adapted to be secured over the pockets to prevent access to the interior thereof by cutting, tearing, ripping, etc.

With these and other objects in view which will become more apparent in the following description and disclosures in the drawings, this invention comprises the novel mechanism and combinations herein-after described and more particularly pointed out and defined in the appended claim.

In the accompanying drawings which illustrate a preferred embodiment of this invention and in which similar reference numerals refer to similar parts in the different views:

Figure 1 is a section through a garment such as a pair of trousers showing the application of our invention.

Figure 2 is a top plan view of the cooperating members upon an enlarged scale.

Figure 3 is a vertical section through said members substantially upon the line 3—3 of Figure 2.

Figure 4 is a view substantially on the line 4—4 of Figure 3 with parts in elevation.

Figure 5 is a section substantially on the line 5—5 of Figure 2 with parts in elevation.

As shown on the drawings:

In the exemplification of this invention, we have illustrated a hollow button-like disk as member 1 which may be variously constructed. In the present instance, it consists of a circular metal cup-shaped base 1^a having an annular apertured attaching flange 1^b and an annular interior ledge 1^c for supporting a cover or closing plate 1^d substantially flush with the flange 1^b. The cover 1^d may be secured in position by swedging thereon the metal just above the ledge. The base 1^a and cover 1^d are centrally apertured coincidentally and within the chamber formed thereby adjacent the 70 said apertures there is pivoted a latch lever 2 impelled by a spring 3 anchored in an eye stamped from the member 1^a. The spring 3 yieldingly urges the latch lever over a portion of said apertures as shown 75 in Fig. 4. The latch lever 2 is preferably pivoted at one end by bending the end thereof at right angles and inserting it in an aperture in the cover 1^d of the member 1 as shown in Fig. 3. The free end of 80 the latch lever 2 is provided with a lug 4 or portion extending at right angles thereto, which lug extends through an appropriate slot in the cover 1^d, and is provided at its upper end with a small ring 5 to 85 which an operative string or cable is adapted to be attached for moving the latch lever against the tension of the spring 3.

The member 1 is adapted to be secured or attached by means of the flange 1^b to 90 the inner side of a pocket or pouch or the like for the purpose of cooperating with a second member secured directly opposite upon the other side of the pocket or pouch. This second member comprises a substantially flat apertured base 6 having a centrally disposed shank 7 provided with a groove 8 and a convex or rounded head 9. The diameter of the shank 7 corresponds substantially to the diameter of the aperture in the member 1 so that the shank may pass through said aperture; the convex head engaging the side of the latch lever 2 and forcing or snapping it back 100 against the tension of the spring during such operation. When the shank 7 has been passed through said aperture as far as it can go, the spring 3 will force the latch over into the groove 8 whereby the two cooperating members become locked together, 110

and in order to separate the same, it is necessary to withdraw the latch lever 2 from the groove 8 by exerting a pull upon the ring 5.

5 In Figure 1 is illustrated an application of this invention to the hip pocket 10 of a pair of trousers 11. The lug 4 and ring 5 extend through the inner side of the pocket, the ring having attached thereto, a cord 12 which is sheathed in a strip of fabric 13 attached to the interior of the body of the trousers and extends around to the front part thereof. When the two members have been snapped together it will be impossible for anyone to open or get into the pocket without pulling on the cord 12, and as this lies and is concealed upon the inner side of the garment, and is only operable at the front part of the garment, it becomes 20 impossible for a thief to pick a pocket that is locked according to this invention.

We are aware that numerous details of construction may be varied through a wide range without departing from the principles of this invention, and we therefore do not purpose limiting the patent granted otherwise than necessitated by the prior art.

We claim as our invention:

In combination, a garment having a rear

pocket, a hollow member secured to the inner side of said pocket, said member comprising a cup-shaped base, a cover for the cup portion thereof, and a spring-impelled latch pivoted in the chamber formed between said base and cover and formed with a lug at its free end extending through a slot in said cover, said latch normally intersecting a portion of the coincident central apertures in said base and cover, a cord attached to the free end of said lug and disposed in a sheath formed in said garment and extending to the front thereof, and a second element attached to the other side of said pocket and comprising a base and a grooved shank, the latter adapted to be inserted into the central apertures in said first member to be engaged and locked therein by said latch, said cord affording means for retracting said latch to unlock said members.

In testimony whereof, we have hereunto subscribed our names in the presence of two subscribing witnesses.

CARL B. ERICKSON.
CARL J. WITT.
